UNITED STATES PATENT OFFICE.

DAVID W. SOLOMON, OF REDMOND, WASHINGTON.

SAW SUPPORT AND GUIDE.

Application filed February 12, 1921. Serial No. 444,603.

To all whom it may concern:

Be it known that I, DAVID W. SOLOMON, a citizen of the United States, residing at Redmond, in the county of King and State 5 of Washington, have invented certain new and useful Improvements in Saw Supports and Guides, of which the following is a specification.

This invention relates to a support and 10 guide for a saw when under cutting, and its object is the provision of an inexpensively constructed and efficient device of this character.

The invention consists in a saw guide 15 adapted to be attached to the handle of an axe which, upon being engaged in a log, constitutes the saw supporting member.

The invention further consists in the novel construction, adaptation and combination 20 of parts as will be hereinafter described and claimed.

In the accompanying drawings, Figure 1 is a plan view showing a saw-guide embodying the preferred form of my invention in 25 use. Fig. 2 is a view of the same shown partly in side elevation and partly in section, said section being taken through line 2-2 of Fig. 1. Fig. 3 is a plan view to a larger scale of the saw-guide illustrated 30 in Figs. 1 and 2. Fig. 4 is an end elevation of Fig. 3, with the guide applied to an axe handle which is illustrated in transverse section. Fig. 5 is a perspective view of the saw bearing block shown detached.

35 Fig. 6 is a plan view showing a modified form of the invention secured to an axe handle; and Fig. 7 is a longitudinal vertical section of Fig. 6.

The reference numeral 10 designates an 40 axe the head 11 of which is engaged in a log L so that the axe handle 12 will occupy approximately the relative position in which it is represented in Fig. 1.

Said handle provides the support for a 45 saddle block B, which serves as a guide for a saw S. The under surface 13 of said block is formed to a concavity to fit against the axe handle, or nearly so, and the upper surface 14 is made of a general convex shape. 50 Protruding from such upper surface is a plurality of ridges 15 disposed right angularly to the longitudinal axis of the block and to the supporting axe handle to which the block is attached. Said ridges are of

greater depths at the midwidth of the block 55 than at the side edges 16 of the block and are furthermore of greater widths at their midlengths so as to afford between the adjacent ridges a groove 17 which flares from the midwidth of the block toward both sides of 60 the latter thereby providing a guideway for a saw blade which will enable the latter to be reciprocated at selected angles with respect to the block and at approximately 65 right angles to the log.

The upper surface of the block between the ridges 15 thereof is provided with cavities 18 which serve as receptacles for oil for the purpose of lubricating the back, or unserrated edge, S¹ of the saw blade 70 when in operation.

The device as shown in Figs. 1 to 4, inclusive, is detachably connected to an axe handle by a strap 19 and buckle 20. Said strap is slotted to provide a recess through 75 which the ridges 15 of the block extend, and with the strap elements 19¹ at each side of the slot secured to the block as by means of bolts 21.

When unemployed the device shown in 80 the views above referred to may be readily removed from the axe handle, and may be shifted longitudinally upon the handle. This feature of the invention is of importance in practice as it enables the operator 85 to readily produce two undercuts in close relations to each other in the event of a tendency in the log to pinch or clamp the saw.

Where it is desirable to permanently retain the saw guiding device upon the handle, the modified form of block shown in Figs. 6 and 7 may be advantageously used. In this embodiment the block is 90 formed with a multiplicity of ridges with intervening saw guiding grooves or guideways, and is secured to the axe handle by screws 22 or an equivalent. In the construction just described the block is made somewhat thinner than with the removable type 95 in order that the axe may be conveniently used for chopping, trimming branches, etc.

The invention has many advantages over 100 other appliances hitherto in use for supporting and guiding saws in undercutting, 105 it has no rollers or wheels and is durable, is not subject to derangement, and safeguards the handles of axes from torsional strains

or from becoming mutilated by preventing the saw blade from contacting with an axe handle.

What I claim, is:—

- 5 A saw guide and support, comprising a saddle-shaped block adapted to seat upon an axe handle, the convex surface of the block being provided with a saw-guiding groove arranged right angularly to the lon-

gitudinal axis of the block, said block being provided with cavities for a lubricant, and means to secure said block in place.

Signed at Seattle Washington, this 27th day of December 1920.

DAVID W. SOLOMON.
